UNITED STATES PATENT OFFICE

95,602

DESIGN FOR A JIG SAW

William J. Merrigan, Los Angeles, Calif., assignor
to Herberts Machinery Co., Ltd., Los Angeles,
Calif.

Application January 23, 1935, Serial No. 55,019

Term of patent 14 years

To all whom it may concern:

Be it known that I, William J. Merrigan, a citizen of the United States, residing at Los Angeles, in the county of Los Angeles and State of California, have invented a new, original, and ornamental Design for Jig Saw, of which the following is a specification, reference being had to the accompanying drawings, forming part thereof.

Fig. 1 is a view in side elevation of the improved
jig saw embodying my design.

Fig. 2 is a top plan view of the same.

Fig. 3 is a view in front elevation of the jig saw.

Fig. 4 is a view in rear elevation of the same.

I claim:

The ornamental design for a jig saw, as shown.

WM. J. MERRIGAN.
